UNITED STATES PATENT OFFICE.

CHARLES WILLIAM EDWARDS, OF MAQUOKETA, IOWA.

ANCHOR.

1,137,745.

Specification of Letters Patent.

Patented May 4, 1915.

Application filed March 4, 1914. Serial No. 822,419.

To all whom it may concern:

Be it known that I, CHARLES W. EDWARDS, a citizen of the United States, residing at Maquoketa, in the county of Jackson and State of Iowa, have invented a new and useful Anchor, of which the following is a specification.

The present invention appertains to anchors, and especially those for anchoring fence posts, telegraph and telephone poles, and the like, to the soil.

It is the object of the present invention to provide an anchor of the nature indicated, which will be of improved and unique structure, whereby the same may be embedded or implanted in the soil, without the necessity of digging a hole in the soil, as is necessary with common anchors.

As a more specific object, the present invention aims to provide an anchor embodying a member adapted to be driven into the soil, or object to which the anchor is to be applied, in connection with a second member assembled with the aforesaid member in a unique manner, whereby when the second member is driven, the same will provide a hook or prong engaging the soil in such a manner, as to lock the anchor in place.

The present invention comprehends the provision of an anchor of the character specified, which will be comparatively simple and inexpensive in construction, which may be normally assembled in such condition, that it may be readily transported or handled with the parts intact and in condition for driving, which may be readily driven into the soil, and which will be simple, convenient, serviceable, practical and efficient in its use.

With the foregoing and other objects in view which will appear as the description proceeds, the invention resides in the combination and arrangement of parts and in the details of construction hereinafter described and claimed, it being understood that changes in the precise embodiment of the invention herein disclosed, can be made within the scope of what is claimed, without departing from the spirit of the invention.

The invention has been illustrated in its preferred embodiment in the accompanying drawings, wherein:—

Figure 1 is a side elevation of the anchor showing the parts as assembled for ship-

ment and preparatory to driving, portions being broken away. Fig. 2 is another elevation of the anchor, taken at right angles to the line of view of Fig. 1. Fig. 3 is an enlarged fragmental detail illustrating the deflecting anvil and the lower end portion of the key or locking bar. Fig. 4 is a side elevation of the anchor as applied to the soil.

In carrying out the present invention, there is provided a flat anchor bar 1, of relatively rigid or stiff material, the same being relatively thick and wide, and being adapted to be driven into the soil. The lower end of the bar 1 is sharpened, to facilitate the driving of the bar into the soil. An upwardly projecting tongue 2 is struck from the bar 1, adjacent its lower or sharpened end, and this tongue 2 is bent on a compound curve, to provide a deflecting anvil 3 upon the inner side of the tongue, the tongue 2 being struck from the bar 1, providing an opening or passage 4 adjacent the deflecting anvil 3. The tongue 2 is relatively rigid or substantial so as to be unyielding to the strains to which it is subjected. The anchor embodies a second flat bar 5, which is relatively thin and narrow, and which normally rests against one side of the anchor bar 1. The bar or strip 5, which constitutes the key or locking element, and the anchor bar 1, are provided with alining apertures 6 adjacent the upper ends of the bars, and a wire or binding element 7 is engaged through the apertures 6, and is wound around the upper end portions of the bars 1 and 5, to normally maintain the bars in proper assembled condition. The removable wire or binding element 7 holds the upper ends of the two bars together, to thereby prevent relative longitudinal movement between the said bars, and to hold the lower end of the bar 6 in engagement with the anvil 3.

The lower end portion of the bar 5, is malleable or bendable, and the lower extremity of the said bar is sharpened and bent slightly, as at 8, to engage the deflecting anvil 3 and partially enter the opening 4. Thus, the lower end portion of the locking bar 5 is maintained in operative relation with the anvil and opening, which, in connection with the temporary locking or holding means 7, retains the locking or key bar 5 in assembled condition with the anchor bar 1. The upper end of the locking

bar 5 projects above the upper end of the anchor bar 1, when the bars are assembled as illustrated in Figs. 1 and 2. The anchor is adapted to be shipped or transported in this condition, whereby the anchor may be readily driven into the soil, by any inexperienced person, without the necessity of assembling the parts of the anchor, unless they have been detached.

- 10 To embed or implant the anchor in the soil, the anchor bar 1 is driven into the soil, at the position desired, by striking the upper end of the anchor bar 1 with a sledge or other suitable implement, the locking or 15 key bar 5 being carried into the soil with the anchor bar 1, due to the fact that the lower end of the bar 5 is engaged behind the tongue 2 and within the opening 4 of the bar 1, and due to the fact that the wire 20 or locking means 7 is not released, until the bars have been properly driven into the soil. Then, when the anchor bar 1 has been driven sufficiently into the soil, with its upper end protruding, the holding or retaining wire 25 7 is removed, the upper portion of the bar 5 then being held against the side of the bar 1, due to the engagement of the bar 1 with the soil. The bar 5 is then driven downwardly along the anchor bar 1, this being 30 readily accomplished due to the upper projecting end of the bar 5, and which will result in the lower end portion 8 of the bar 5 being deflected laterally through the opening 4, to form a hook or claw 9 engaging 35 the soil in such a manner as to lock the anchor bar 1 in place, to prevent its withdrawal or disengagement from the soil. It will be noted that when the bars 1 and 5 are assembled, preparatory to driving, the lower 40 extremity 8 of the bar 5 is curved slightly, so as to be started into the opening 4, whereby when the bar 5 is driven, the lower end portion of the said bar will be deflected laterally through the opening 4, by the deflecting anvil 3, the lower end of the bar 5 45 being sharpened, so as to readily enter or penetrate the subsoil. The lower end portion of the bar 5 is malleable, so as to bend

or flex readily due to the engagement of the bar with the deflecting anvil 3. After the 50 locking bar 5 has been driven inwardly, as illustrated in Fig. 4, to provide the hook 9 engaging the subsoil, to anchor the device firmly in place, a guy 10 may be engaged through the aperture 6 of the anchor bar 1. 55

The present anchor may be employed in numerous capacities, such as for anchoring fence posts, telephone and telegraph poles, windmill towers, and the like, to the soil.

It is evident from the foregoing, that the 60 anchor may be embedded or implanted in the soil, without the necessity of digging a hole to receive the anchor, as is necessary with anchors now in use. The anchor may also be employed as a spike or nail, when 65 constructed in a sufficiently small size, in order that the device may be driven into wood or other similar material, to anchor therein, the same as results when the device is driven into the soil in the manner above described. 70

From the foregoing, taken in connection with the drawing, the several advantages and capabilities of the present device will be obvious to those versed in the art, and further comment is deemed unnecessary, it 75 being noted that the objects aimed at have been carried out satisfactorily.

Having thus described the invention, what is claimed as new is:—

An anchor comprising a flat rigid anchor 80 bar having a tongue struck therefrom adjacent its lower end and forming a deflecting anvil and an opening coöperating with the anvil, a flat locking bar adapted to be driven along one side of the anchor bar and 85 having a lower flexible end portion engageable with the said anvil to pass through the said opening.

In testimony that I claim the foregoing as my own, I have hereto affixed my signature in the presence of two witnesses.

CHARLES WILLIAM EDWARDS.
